(57) **CLAIM**

The ornamental design for a three-headed camera system, as shown and described.

DESCRIPTION

FIG. 1 is a top front perspective view of a three-headed camera system showing my new design;

FIG. 2 is a bottom front perspective view thereof;

FIG. 3 is a top rear perspective view thereof;

FIG. 4 is a bottom rear perspective view thereof;

FIG. 5 is a front elevated view thereof;

FIG. 6 is a rear elevated view thereof;

FIG. 7 is a top plan view thereof;

FIG. 8 is a bottom plan view thereof;

FIG. 9 is a right elevated view thereof; and,

FIG. 10 is a left elevated view thereof.

The broken lines showing of fasteners and connectors in FIG. 1-10, and the broken lines showing of a camera in FIG. 1-10 are included for the purpose of showing environmental structure and form no part of the claimed design.
